UNITED STATES PATENT OFFICE.

ACHILLE F. BIAVATI, OF FREEPORT, NEW YORK.

DEVICE FOR HANDLING AMUSEMENT-CARS.

No. 895,946.

Specification of Letters Patent.

Patented Aug. 11, 1908.

Application filed April 13, 1908. Serial No. 426,776.

To all whom it may concern:

Be it known that I, ACHILLE F. BIAVATI, a citizen of the United States, and a resident of Freeport, in the county of Nassau and State of New York, have invented a new and Improved Device for Handling Amusement-Cars, of which the following is a full, clear, and exact description.

This invention relates to amusement machinery, my more particular purpose being to provide a means for readily handling the cars employed.

More particularly stated, my invention comprises apparatus for lifting a car from one level to another, so as to bring the support of the car into registry with a railroad track, then tilting the supporting mechanism so as to cause the car to glide obliquely downward along the track.

Reference is to be had to the accompanying drawings, forming a part of this specification, in which similar characters of reference indicate corresponding parts in all the figures, and in which

Figure 1 is a front elevation showing a pair of elevators for lifting the cars, and further showing portions of railroad tracks upon which the cars are adapted to glide; Fig. 2 is an enlarged fragmentary section upon the line 2—2 of Fig. 3, looking in the direction of the arrow, and showing the car when raised and ready to be released from its support in the elevator; and Fig. 3 is a vertical section upon the line 3—3 of Fig. 2, looking in the direction of the arrow, and showing the arrangement of the supports for automatically holding the car and for guiding the car relatively to the track.

A framework 4, having the form of a double tower, is provided with braces 5, 6, crossing each other, and is further provided with suitable roofs 7, having more or less of an ornamental character. The elevator cars are shown at 8, and are raised and lowered by aid of rods 9.

At 10 are shown gates through which the passengers enter the framework of the elevator.

At 11 are shown the gates for entering the elevator cars.

Mounted within each car 8 is a pair of rocking beams 12, said rocking beams being connected by hinges 13 with a floor beam 14. Interposed intermediate of the rocking beams 12, is a third rocking beam 15 of slightly greater width than the others. Connecting

together the rocking beams 12, 15, are cross beams 16. These cross beams and the rocking beams together constitute a strong platform. Extending upwardly from this platform are standards 17, and carried by the latter are side beams 18, which, of course, move with the platform, being otherwise rigid. A center rail 19 is mounted upon the beam 15. A car 20, having in this instance the shape of a boat, is provided with a keel portion 21, and journaled within the same are wheels 22, each wheel being provided with two flanges 23, and running upon the rail 19 in such manner that the flanges 23 are disposed upon opposite sides of the same. Mounted upon the sides of the car 20, are brackets 24, and journaled within the latter are rollers 25, which engage the inner faces of the beams 18.

Mounted in the bottom of the elevator car is a beam 26, and connecting this beam with the adjacent beam or rail 19, are toggle links 27, 28, 29, arranged in pairs, as indicated in Fig. 2, the links of one pair being longer than those of another pair. The lower toggle links are mounted rigidly upon stub shafts 30, 31, 32. Arms 33, 34, 35, are mounted upon these stub shafts, these arms all being of the same length, and connected together by a rod 36. This rod is connected with the lower end of a lever 37, this lever being journaled at 38 upon the beam 12, and being provided with a handle portion 39, whereby the lever and parts connected with it, may be actuated.

At 40 are rails adapted to be brought into registry with the beams 18, and at 41 is a stationary beam corresponding to the beam 12 and provided with a rail 42, said last-mentioned rail corresponding in cross section with the rail 19 and registering therewith when the elevator is in the position indicated in Fig. 2.

The operation of my device is as follows: The elevator car being in its lowermost position, the gates 10 are opened, and the passengers enter the elevator car and take their seats. The gates 10 are now closed, and the elevator car lifted in a manner well understood in this art. Arriving at the upper level (see upper left-hand portion of Fig. 1), the operator now grasps the handle 39 and draws it to the left, according to Fig. 2. The lever 37 thereupon forces the rod 36 to the right, turning the arms 33, 34, 35, and moving the various toggles, as indicated in Fig.

2. The platform carried by the toggles is thus elevated, the right-hand portion of the platform being raised a considerable distance as compared with the central portion 5 thereof, thus tilting the car 20. The beams 18 having been alined with the guide rails 40 and the rail 19 being likewise in alinement with the rail 42, the car simply runs downwardly by its own gravity. The rollers 25 10 engaging the beams 18, or rails 40, keep the car always in its proper position, and the wheels 22 are unable to leave the central rail 19 or the central rail 42, because of the action of the flanges 23.

15 Having thus described my invention, I claim as new and desire to secure by Letters Patent:

1. The combination of an elevator car, a platform mounted therein and movable relatively thereto, a plurality of separate toggle joints, each connected with said elevator car and with said platform, means controllable at will for actuating all of said toggle joints at the same time, and a car mounted temporarilly upon said platform and adapted to run therefrom by its own weight, when said platform is tilted.

2. The combination of an elevator, provided with a member movable vertically, rails connected with said member and disposed opposite each other, a car mounted

intermediate said rails and provided with rollers for engaging the same, said rollers extending in opposite directions from said car rails disposed adjacent to said elevator and adapted to be alined with said rails connected with said elevator, a track for supporting said car, and means for starting said car from said elevator relatively to said track.

3. The combination of a stationary track, 40 an elevator car disposed adjacent thereto, a fragmentary track mounted within said elevator car, means for inclining said fragmentary track, a passenger car normally supported upon said fragmentary track rails 45 carried by said elevator car and disposed on opposite sides of said passenger car, rollers mounted upon said passenger car and adapted to engage said rails, other rails mounted fixedly in position and adapted to register 50 with said rails carried by said elevator car, and a track mounted fixedly in position and adapted to register with said fragmentary track carried by said elevator car.

In testimony whereof I have signed my 55 name to this specification in the presence of two subscribing witnesses.

ACHILLE F. BIAVATI.
